Primary Examiner — Robert M Spear*Assistant Examiner* — Darcey E Heflin(74) *Attorney, Agent, or Firm* — Ward and Smith, P.A.;
Ryan K. Simmons(57) **CLAIM**

The ornamental design for a compartmented carton insert, as shown and described.

DESCRIPTION

FIG. 1 is a perspective view of a compartmented carton insert showing a new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof showing the compartmented carton insert in another configuration; and, FIG. 9 is another top view thereof showing the compartmented carton insert in another configuration.

The dashed lines are included for the purpose of illustrating portions of the compartmented carton insert that form no part of the claimed design.

1 Claim, 6 Drawing Sheets(56)
